UNITED STATES PATENT OFFICE.

JAMES D. WADE, OF GONZALES, TEXAS.

PACKER FOR PUMPS.

Application filed May 11, 1923, Serial No. 638,255. Renewed March 10, 1925.

To all whom it may concern:

Be it known that I, JAMES D. WADE, a citizen of the United States, residing at Gonzales, Gonzales County, Texas, have invented 5 a certain new and useful Improvement in Packers for Pumps, of which the following is a full, clear, and exact description, such as will enable others skilled in the art to which it appertains to make and use the 10 same.

My invention relates to an improvement in packers to be used on pumps of the type disclosed in my co-pending application for patent, Serial Number 622,072, filed March 15 1st, 1923 on the method of and apparatus for pumping wells. In this system of pumping the upper end of the pump barrel is sealed against the inner wall of the casing at the lower end of the well, and no tubing 20 is used, the plunger being lowered into the upper end of the pump barrel thus sealed to the casing, and the casing itself acting to furnish an outlet for the oil in the same manner that the tubing does in the usual 25 method of pumping.

It is an object of my invention to provide a seal or packer for the upper end of the pump barrel, adapted to close the space between the upper end of the pump barrel and 30 the liner and casing, so that no leakage of fluid will result.

Another object is to provide a packer of this type which may be easily expanded and which will remain in contracted position 35 until the setting of the device is desired.

Another object is to provide an additional seal between the packer and the pump barrel which will prevent the passage of fluid and to also provide an outlet for gas under pressure, so as not to interfere with the operation 40 of the pump.

Further objects and advantages, and the means by which these objects are carried out, will be set forth with greater clearness in 45 the specification which follows:

Referring to the drawing herewith, wherein like numerals are applied to like parts in all the views, Fig. 1 is a central longitudinal section through the upper end of the 50 pump barrel, showing my packer before the same has been expanded; Fig. 2 is a similar view showing the packer in expanded position and Fig. 3 is a broken detail showing a central section through the gas valve em- 55 ployed with my invention.

In the use of my device it is customary to drill down to the pay stratum, to form a full-sized hole above the pay, and to then set the casing to support the walls of the well above the pay stratum, and to seal off 60 the entrance of fluid to the well. The pay stratum is then drilled into with a bit of smaller diameter, and a liner is set in the smaller hole thus drilled; this liner having a screen attached thereto, or being perforated to allow entrance of fluid.

In the drawing the casing is represented by the numeral 1 and the liner 2 extends upwardly into the casing for a short distance. In sealing the space between the liner and 70 casing I set my packer by dropping it into the well until it comes in contact with the upper end of the liner. I employ a mandrel 3, the upper end of which is cylindrical, and the central portion of which is tapered inwardly from the upper portion toward the lower end, as shown at 4. The lower end of the mandrel 5 is cylindrical for a short distance to provide a seat for a cylindrical ring 6. This ring is slidable for a 75 limited space on the mandrel and is held normally in position at the lower end by means of pins 7, which extend through the ring and into the mandrel for a short distance. These pins are of frangible material, 80 easily sheared off when a blow is delivered against the ring 6.

Above the ring 6, and fitting upon the tapered portion 4 of the mandrel is a packer sleeve 8, which may be made of any compressible material, but which I contemplate forming of soft metal, such as lead. This packing sleeve is cylindrical on the outer surface, and it will be noted that the upper cylindrical end 3 of the mandrel, the outer 95 surface of the packer, and the ring 6, together provide a cylindrical surface which fits loosely the interior of the casing.

The upper end of the mandrel is beveled inwardly at 9 and the said beveled surface 100 is cut by a plurality of serrations 10 extending around the upper end of the mandrel and furnishing a seat for a lead packing ring which will be presently described.

The pump barrel 11 is of comparatively 105 small diameter and fits loosely through the central passage 12 in the mandrel. At its upper end it is secured by means of a collar 12 to the lower end of the nipple 13. This nipple is of the same diameter as the work- 110

ing barrel at its lower end, and is swedged outwardly at 14 to form a guide barrel 15 of larger diameter to receive and guide the plunger into the working barrel. The walls 5 at the upper end of the guide barrel are thickened at 16 so as to loosely fit within the casing. The lower shoulder 17 provided by the thickening of the walls is formed with an annular mortice 18 therein to provide at 10 attachment for a packing ring 19 which I contemplate forming of lead or some composition of soft metal which may be compressible. The outer wall of the guide barrel 15 is serrated at 20 to further support the pack- 15 ing ring 19. This packing ring is tapered on its lower surface at 21 to fit within the beveled seat 9 provided in the upper end of the mandrel 3. The inner upper end of the guide barrel is enlarged and threaded at 22 20 to provide attachment for a setting tool or drill stem, not shown.

The tapered or swedged portion 14 in the nipple 13 is provided with an opening 23 therein, which is threaded to receive a valve 25 chamber 24, the inner end of which is formed into a tapered seat 25 for a valve 26, held resiliently in its seat by means of a spring 27. It will be noted that this valve is adapted to open inwardly to allow the entrance of gas under pressure to the pump barrel. The upper end of the passage through 15 may be recessed slightly to seat a sleeve 28, normally covering openings 29. This sleeve forms a valve which may be 30 raised by means of a spear or other tool to allow the fluid inside the casing to run back when the pump barrel is to be withdrawn. 35

In the operation of my device, the packing sleeve comprising the mandrel and the ring 40 6, as assembled in the manner shown in Fig. 1, is dropped downwardly into the upper end of the casing. It is contemplated that this packer will drop with some velocity, so that when the ring 6 contacts with the upper end 45 of the liner 2 it will have sufficient force to break the frangible pins 7 and force the ring upwardly on the mandrel so as to expand the packing sleeve 8, in an obvious manner.

The pump barrel is then assembled, as 50 shown in Fig. 1, upon the lower end of the nipple 13, and is lowered at the end of a setting tool or drill stem to its position in the bottom of the well. It is contemplated that it will be lowered with some force so 55 as to drive the lower tapered face of the ring 21 into the serrated seat formed at 10 on the upper end of the mandrel. This will serve, in an obvious manner, to compress the lead ring into the serrations on the seat and 60 form a tight fit, as shown in Fig. 2. Furthermore, if the packer has not been properly expanded, it will serve to further compress the packer and seal off the space around the upper end of the liner. The

parts will then be in position shown in 65 Fig. 2.

It will be noted that there will be no outlet for fluid outside of the liner and around the lower end of the casing. The pump plunger may then be lowered down into the 70 well, passing through the guide barrel 15 into the pump barrel, where it may be operated in the usual manner. The valve 26 will allow gas under pressure within, the space around the nipple to escape into the 75 casing above the plunger and will thus not interfere with the action of the tool. Furthermore, it will prevent back pressure of gas against the strata, in sufficient amount to prevent the inflow of oil. 80

It will be noted that the device thus provided is easily and accurately operated, and formed to provide an accurate and durable seal so that the pump may be operated for long periods of time without interruption. 85 If, however, it is necessary to withdraw the pump barrel for any purpose, this may be done by engaging the setting tool in the upper end of the socket 22, and by use of a jar the parts may be separated and withdrawn from the well. 90

Having thus described my invention, the further objects and advantages of which will be apparent to one skilled in the art, what I claim as new and desire to protect by Letters Patent is:

1. A packer for pumps comprising a downwardly tapered hollow mandrel, a ring 100 slideable thereon, means to normally secure said ring to said mandrel, a packing sleeve 105 of ductile metal above said ring, a tapered seat at the upper end of said mandrel, a pump barrel, a nipple at the upper end thereof, and a shoulder of soft metal on said nipple shaped to fit said tapered seat for the 110 purpose described.

2. In a pump, a casing, a liner projecting into the lower end of said casing, a mandrel having a downwardly tapered surface thereon, a cylindrical portion below said tapered surface, a ring slideable thereon, frangible means to retain said ring on said lower end and a packing sleeve of compressible material above said ring adapted to be forced upwardly and expanded when said ring is 115 advanced upwardly on said mandrel by contact with said liner.

3. In a pump, a casing, a liner projecting upwardly into the lower end of said casing in combination with a packer comprising a downwardly-tapered hollow mandrel, a sleeve of compressible material thereon, means below said sleeve adapted to support said sleeve, whereby said mandrel may be forced downwardly therein by gravity to expand said sleeve, a tapered seat in said mandrel, a pump barrel and means secured to said pump barrel adapted to fit within 125

said seat and form a closed seal therewith.

4. In a pump, a casing and liner, means to seal the space between said casing and liner, including a hollow mandrel, a tapered seat in the upper end thereof, a pump barrel, a nipple thereon, an enlarged head on said nipple and a tapered lower shoulder of compressible metal on said head shaped to fit within said seat.

10 5. In a device of the character described, a casing, a liner, means to seal the space between said casing and liner including a hollow mandrel, a tapered seat in the upper end of said mandrel having annular grooves therein, a pump barrel in said liner and a nipple on the upper end of said pump barrel having a lower tapered shoulder

shaped to fit in said tapered seat and a ring of soft metal on said shoulder adapted to be compressed into said grooves. 20

6. In a device of the character described, a casing, a packer adjacent the lower end thereof including a hollow mandrel, a packing sleeve thereon, a tapered seat in the upper end of said mandrel, a pump barrel 25 extending freely through said mandrel, a nipple on said barrel enlarged above the lower end, and a shoulder on said nipple having a soft metal facing thereon adapted to fit within said seat and make a tight 30 closure therewith.

In testimony whereof, I hereunto affix my signature this 7th day of May, A. D. 1923.

JAMES D. WADE.
